By his Attorney

Franklin D. Lang

UNITED STATES PATENT OFFICE.

ROBERT STEVENSON, OF ANSLEY, NEBRASKA.

DOOR-CHECK.

SPECIFICATION forming part of Letters Patent No. 426,339, dated April 22, 1890.

Application filed February 8, 1890. Serial No. 339,672. (No model.)

To all whom it may concern:

Be it known that I, ROBERT STEVENSON, a citizen of the United States, residing at Ansley, in the county of Custer and State of Nebraska, have invented certain new and useful Improvements in Door-Regulators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in door-securers of that class adapted to hold a door in any desired position and by which it may be securely fastened shut when desired.

20 The objects of the invention are to provide a securer cheap and simple in construction, especially adapted for use upon front doors of dwelling-houses, where it is desired to leave open the doors of the house for the admission 25 of air, and at the same time render it impossible for any one to enter the house, and for store-doors which open against the show-cases, by which the door may not hit the case and damage the same.

30 To these ends, and to such others as the invention may pertain, the same consists in the novel combination and in the peculiar construction, arrangement, and adaptation of parts, all as more fully hereinafter described, 35 shown in the accompanying drawings, and then specifically defined in the appended claims.

The invention is illustrated in the accompanying drawings, which, with the letters of 40 reference marked thereon, form a part of this specification, like letters of reference indicating like parts throughout the several views, and in which—

45 Figure 1 is a perspective view of a door and its frame, showing my invention, the door being secured part way open. Fig. 2 is a detail view of the spring-actuated catch, showing the spring and catch exposed, the covering or housing being broken away.

50 Reference now being had to the details of

the drawings by letter, A is a door of ordinary and well-known construction, and B its frame.

C is a semicircular metallic piece, preferably of brass, the ends of which D are bent inwardly and are secured to the frame of the 55 door when in use. Upon the underside of the said piece are notches e, adapted to receive a spring-actuated catch, hereinafter described.

E is a brace, preferably of metal, secured between the semicircular portion and the inwardly-bent ends of the same, and adapted to strengthen the securer. Upon the said semicircular piece is sleeved the adjustable block F, which block is provided with a thumbscrew G, by means of which it may be adjusted, and a triangular-shaped rubber H, against which the door will strike when open.

I is a metallic plate secured to the inner face of the door, upon the surface of which the spring-actuated catch J moves. Said catch is 70 provided upon one side with a notch j, adapted to hold the catch out of its engagement with the semicircular piece C when drawn down and pressed to the left, as will readily be seen. Upon the opposite side of the catch is the 75 notch j', against the shoulder of which one end of the spring K, which is preferably of coiled wire, rests, the other end of which spring bears against the covering or housing L of the catch.

80 M is a suitable chain, by means of which the catch is operated.

Having thus described my invention, what I claim to be new, and desire to secure by Letters Patent, is—

85 1. The combination, with a door and its frame, of a semicircular metallic piece secured to said frame, provided with notches upon its under side adapted to receive a spring-actuated catch secured to the inner face of the 90 door, and an adjustable block sleeved upon said semicircular metallic piece adapted to limit the swing of the door, substantially as described, and for the purpose specified.

95 2. The combination, with a door and its frame, of a semicircular metallic piece secured to said frame, provided with notches upon its under side, said notches having beveled sides for the reception of a spring-actuated catch secured to the inner face of the door, an ad- 100

justable block sleeved upon said semicircular piece provided with a thumb-screw, as shown, and a triangular-shaped rubber upon the inner face of said block, substantially as and for the purpose specified.

3. The combination, with a door and its frame, of a semicircular metallic piece secured to said frame, provided with notches having beveled sides upon its under side adapted to receive a spring-actuated catch, said catch being provided with a notch to hold it out of engagement with said semicircular piece, as

shown, and an adjustable block sleeved upon the semicircular piece provided with a thumb-screw and triangular-shaped rubber to limit 15 the swing of the door, substantially as described, and for the purpose specified.

In testimony whereof I affix my signature in presence of two witnesses.

ROBERT STEVENSON.
